UNITED STATES PATENT OFFICE.

GEORGE JOSEPHUS JOHNSON AND EUGENE HOWELL THOMAS, OF LA CROSSE,
WISCONSIN.

DRAW-GEAR FOR RAILWAY-CARS.

SPECIFICATION forming part of Letters Patent No. 290,241, dated December 18, 1883.
Application filed August 2, 1883. (No model.)

To all whom it may concern:

Be it known that we, GEORGE J. JOHNSON and EUGENE H. THOMAS, residing at La Crosse, in the county of La Crosse and State of Wisconsin, have invented a new and useful means of preventing the withdrawal of draw-bars for coupling trains together, of which the following is a specification.

Our invention relates to improvements in the means of preventing draw-bars connecting cars together from being pulled or drawn out; and it consists in the novel arrangement and combination of parts, as hereinafter described, and specifically set forth in the claim. We attain these objects by the mechanism illustrated in the accompanying drawing, in which—

The figure is a plan view of our improvement.

Similar letters refer to similar parts.

In the drawing, A A represent the sills or draft-timbers of an ordinary car, and B the draw-bar formed at its front end, preferably in the manner here shown. The bar B, at its outer portion, is adapted to slide longitudinally, and is supported upon cross-pieces L, suitably secured to the sills A.

To each of the inner sides of the sills A are secured or made integral therewith inwardly-extending pieces or lugs I I' I'', placed at sufficient distances apart, and connected together on both the top and bottom sides by means of longitudinal strips or plates I'', which thus form, when connected, rectangular slots i on each of the inner sides of the sills and between the projections I I' and I I''.

To the rear end of the draw-bar B is secured a longitudinal rod or bolt, G, screw-threaded at its end, the said bolt being adapted to pass through the cross-pieces H and a band or plate, E, and thus allow the bar B to have a longitudinal play by means of the pieces H sliding both backward and forward in the slots i.

Between the cross-pieces H H and winding around the rod G is a spiral spring, F, the purpose of which will be hereinafter more fully described.

To the rear end of the draw-bar B is secured,

both on its upper and lower sides, a plate or cap-piece, E, passing over and extending 50 around the cross-pieces H.

In front of the plate E, and on each side of the rear portion of the bar B, are two tapering lugs, D, provided with seats d, and which are made preferably in the manner here shown, 55 and are cast either with the bar or secured thereto by any suitable means, as may be found most desirable.

On the inner sides of the sills A, and in front of the lugs D, are formed with or secured thereto lugs C, made almost similar in shape to the lugs D, but facing in opposite directions, thereby adapting the lugs D and C to engage with each other in case of the bar B being drawn or pulled out to a sufficient distance. It will thus 60 be seen that, even should the nut on the rod G or the spring F become worn or by accident broken, the bar B would still be held in its position by means of the lugs becoming engaged with each other, and which would thus prevent 65 70 accidents.

In connecting or coupling cars together, to prevent the bar B from being pushed backward too far, small inclined lugs K are formed on the lugs I I', which are adapted to engage 75 or come in contact with the inclined portion of the lugs D. We have here shown the longitudinal pieces I I and lugs C C as being in separate pieces; but we may, should it be found preferable, cast or mold them in one continuous piece, which would in some cases be found more advantageous and tend both to save time and trouble.

The several parts here enumerated may be made of any material found suitable—such, for 85 instance, as steel, brass, wrought or cast iron, and the like.

By our invention all danger of the draw-bar becoming disconnected from its position is averted, thereby preventing accidents from 90 such causes, as is now generally the case, and which we consider as an important feature, and one of great necessity.

We are aware that draw-bars have been connected to sills by cross-pieces, and having 95 springs for preventing shock, and we there-

fore do not desire to claim any such feature, broadly; but

What we do claim, and desire to secure by Letters Patent, is—

- 5 In a draw-bar for connecting cars together, the sills A A, having the lugs C C, the pieces I I', connected by straps or plates I" I", forming rectangular slots, in combination with the sliding cross-pieces H H and spring F, the
- 10 cap-piece E, connected to the top and bottom of the draw-bar, the rod or bolt G, and the

lugs D D, all substantially as described and for the purposes set forth.

Dated at La Crosse, Wisconsin, this 6th day of June, A. D. 1883.

GEORGE JOSEPHUS JOHNSON.
EUGENE HOWELL THOMAS.
